UNITED STATES PATENT OFFICE

HARRY SCHREIBER, OF NEW YORK, N. Y.

WRIST-WATCH PROTECTOR

Application filed May 23, 1928. Serial No. 279,988.

This invention relates to wrist watch protectors, or the like, and has for an object to provide a device of this character that can be conveniently and quickly attached to a 5 wrist watch and which will effectively serve as protective means from dust, moisture or other foreign matter.

A further object of this invention is to provide an article of the above described character that can be applied to all forms of wrist 10 watches without changing or injuring the same.

A still further object is to provide a protector with means for securing the same in 15 position and which may be readily unfastened to facilitate the removal of the article.

Still another object of the invention resides in the provision of a protector including a transparent sight opening for exposing the 20 face of the watch, said opening being encompassed by absorptive material to protect the same.

With these objects in view, together with others which will appear as the description 25 proceeds, the invention resides in the novel formation, combination, and arrangement of parts, all as will be described more fully hereinafter, illustrated in the drawings, and particularly pointed out in the claims.

30 In said drawings:

Figure 1 is an elevation of a typical form of wrist watch with my invention applied thereto.

Fig. 2 is a rear elevation of the same and 35 illustrating the means for uniting the fastening means.

Fig. 3 is a rear elevation of the protector removed from the watch; and

Fig. 4 is a central transverse sectional view, 40 taken substantially on the line 4—4 of Fig. 3.

In view of the restriction placed upon watchmakers as to the size of a wrist watch, it has become necessary to compactly arrange the mechanism thereof in a relatively small 45 casing, and hence watches to possess a suitable degree of accuracy must be constructed from high-grade materials, to which their high cost may be readily attributed. Under these conditions it becomes necessary to protect the mechanism thereof from the effects

of moisture, dirt, or the like, and also shocks or jars, to which it is subjected in view of its exposed position on the wearer.

To this end I propose to provide a protective covering for a wrist watch, which may 55 be conveniently applied thereto without injuring or changing the same, and which will permit handy reference thereto when consulting the time.

Referring now in detail to the accompanying drawings, wherein like characters of reference denote similar parts throughout the several views, let 5 denote the face of a typical wrist watch to which latter are connected straps 6 and 7, the former carrying a buckle 65 8 to facilitate the attachment of the time-piece to the wrist of a wearer.

The protector, which comprises the subject matter of this invention, comprises a body portion 9, formed from relatively flexible material, adapted to withstand the effects of moisture, or the like, said body portion 9 being provided with extensions 10 and 11 disposed laterally thereof and adapted to embrace that portion of the straps 6 and 7 75 adjacent their points of connection to said watch.

Suitably secured to each of said extensions 10 and 11, are fastening means 12 and 13, the same comprising strips of flexible material 80 and carrying at their outer ends a typical form of snap-fastener comprising the parts 14 and 15, as clearly shown in Figs. 3 and 4.

In view of the flexibility of the structure as a whole the same may be slipped over the 85 strap 7 and over the watch to the position shown in Fig. 1, the natural or inherent properties of the protector permitting such placement. After the protector has been placed as aforesaid, the fastening means 12 90 and 13 are each wrapped around the extensions 10 and 11, adjacent the juncture of the body portion and said extensions and the parts 14 and 15 secured as shown in Fig. 2. Thus the complete watch is enveloped and 95 protected from extraneous matter such as dirt, moisture or the like.

In order that convenient access may be had to the face 5 of the watch, as for example the 100 consultation of the time, I have provided a

sight opening 16 of sufficient area to expose said face 5 and to this opening I apply a piece of transparent material 17 in order that dust or other accumulations may be positively excluded.

5 From the foregoing it is apparent that the delicate structure of a wrist watch is amply protected and at the same time the function of a watch, to wit: divulging the time, is not 10 in any way or manner impaired.

15 As an additional precaution I propose to surround said sight opening 16 with a frame of absorptive material 18, which may be formed from textile material neatly braided or twisted to add, rather than to detract, 20 from the appearance of the protector. In view of this arrangement any residual moisture will be readily absorbed before passage to said opening.

25 It will, of course, be understood, that said 80 protector may be made in various forms and sizes to conform to the standard casings of wrist watches. It will equally be appreciated that various colors may be adopted in order to enhance the attractiveness of the 85 design.

Having thus fully described my invention, I hereby reserve the benefit of all changes in 90 form, arrangement, order, or use of parts, as it is evident that many minor changes may be made therein without departing from the spirit of the invention or the scope of the following claims:

30 1. A protector for a wrist watch composed 95 of flexible, waterproof material and including a body portion adapted to envelop the casing of a watch, flexible extensions disposed laterally of said body portion and adapted to fit over the straps adjacent said casing, 100 fastening means embracing said extensions, said body portion having a sight opening for exposing the face of the watch and absorptive material arranged marginally of said opening.

40 105 2. A protector for a wrist watch composed of flexible, waterproof material and including a body portion adapted to envelop the casing of said watch, flexible extensions disposed laterally of said body portion and adapted to fit over the straps adjacent said casing, fastening means embracing said extensions, said body portion having a sight opening for exposing the face of the watch, 110 transparent material arranged in said opening, and absorptive material disposed marginally of said opening.

45 115 3. A protector for a wrist watch including a body portion composed of flexible material 120 adapted to encase the exterior of the watch, extensions disposed laterally of said body portion and adapted to fit over the straps carrying the watch, and fastening means embracing said extensions and comprising separable parts adapted to assure a snug fit of

125 said extensions over said straps, said body portion having a sight opening for exposing the face of the watch.

130 In testimony whereof I affix my signature.

HARRY SCHREIBER.
